UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR A COFFIN-PLATE.

SPECIFICATION forming part of Design No. 21,774, dated August 9, 1892.

Application filed July 11, 1892. Serial No. 439,706. Term of patent 7 years.

To all whom it may concern:

Be it known that I, OLIVER McCARTHY, of Meriden, in the county of New Haven and State of Connecticut, have invented a new 5 Design for Coffin-Plates; and I do hereby declare the following, when taken in connection with accompanying drawing, to be a full, clear, and exact description of the same, and which said drawing constitutes part of this specification, and represents a face view.

This invention relates to a design for that part of coffin-trimmings which are in plate form—such, for instance, as the name-plate and the handle-socket plate; and the design 15 consists in the configuration and ornamentation as shown in the accompanying illustration. The body of the plate presents a surface in the form of a parallelogram, and around the body is the representation of a 20 border of floriated scrollwork, the outline of the plate following the configuration of the

said ornamentation, as shown in the accompanying illustration.

It will be understood that the name-plate and handle-plate are the same, except that 25 the handle-plate will be provided with a socket, the socket part being indicated in broken lines; but the construction is immaterial to the design, the outline and ornamentation of the plate being the same in either case. 30

I claim—

The design for coffin-plates, as herein described, and shown in the accompanying illustration.

In testimony whereof I have signed this 35 specification in the presence of two subscribing witnesses.

OLIVER McCARTHY.
